UNITED STATES PATENT OFFICE

SPENCER W. STEWART, OF WHITE PLAINS, NEW YORK, ASSIGNOR TO AMBURSEN CONSTRUCTION COMPANY, INC., OF NEW YORK, N. Y., A CORPORATION OF NEW YORK

DAM

Application filed April 30, 1930. Serial No. 448,459.

This invention relates to a novel and improved form of dam and more particularly to a foundation therefor. The novel features will be best understood from the following description and the annexed drawings, in which are shown selected embodiments of the invention and in which:

Fig. 1 is a fragmentary sectional view through a dam lengthwise thereof, and illustrating prior art practice.

Fig. 2 is a view corresponding to Fig. 1 but showing the practice according to one embodiment of my invention.

Fig. 3 is a vertical sectional view through a dam, this section being taken at right angles to the plane of Fig. 2.

Fig. 4 is a view similar to Fig. 3 but showing a different embodiment of the invention.

Fig. 5 is a view corresponding to Fig. 2 but illustrating the invention as practiced according to the embodiment shown in Fig. 4.

Fig. 6 is a view on the same plane as Fig. 5 but on an enlarged scale.

Fig. 7 is another view on the same plane as Figs. 5 and 6 but on a still larger scale, to illustrate the details of the construction.

At certain sites selected for the construction of dams there is frequently found an area or areas comprising foundation material not capable of taking the full loading put upon it by the dam structure. Such areas frequently occur at portions of a site which is otherwise of excellent material for dam construction. Examples of such areas are furnished by rock, which is different in character from the high-grade rock adjacent it or rock which may be broken or have lines of cleavage not capable of resisting the sliding forces put upon it by the weight of the structure; a faulted condition caused by earthquakes or major earth movements; or a deep narrow gorge filled with earth or other soft material which it would be uneconomical to excavate.

An example of a situation which may be found is shown in Fig. 1, wherein A designates a portion of soft material which may be found in the stream bed across which the dam is being built and which may extend downwardly for a great depth. Adjacent

this material may be found a portion B of broken rock capable of taking more load than the portion A but still not sufficiently good to support the dam structure. On opposite sides of the poor material A and B it is not uncommon to find sound rock areas C. The prior art practice has been to bridge such a fault as shown in Fig. 1 by means of a reinforced beam or slab construction D, upon which is placed the superstructure of the dam here shown as buttresses E.

With such prior art construction, when the load is applied to the beam D, a differential in settlement is very apt to take place because of the difference in character of the foundation material beneath the beam or slab. The moments and shearing stresses caused in the slab are difficult to compute because of this uncertainty as to the support from beneath, and usually they are in actual practice far in excess of those for which the foundation structure was designed, or could be designed economically. The result is, of course, a dangerous condition which may jeopardize the entire structure. Another type of fault is also illustrated in Fig. 1, this fault being exemplified by the line of cleavage F which often occurs with a condition such as shown in Fig. 1, and may, of course, occur independently of the veins of poor foundation material A and B. This plane of cleavage F slopes towards the river bed and represents a fracture underlying a considerable portion of the dam structure. When the dam is under load, there is serious danger that the portion of the structure over the plane F will slide toward the river bed under the influence of the lateral forces induced by the weight of the structure over these planes. This condition has been a serious menace to dams constructed under prior art practice and, so far as I know, no successful and economical way of resisting it has been devised.

Referring now to Figs. 2 and 3, I have shown therein one embodiment of the invention in which it is possible to economically build a foundation for a dam superstructure which will overcome the difficulties discussed above. In this form, I span the river bed or portion containing the poor foundation mate-

rial A and B by a monolithic plug 1 resting on the material A and B and also on the sound rock C on opposite sides of this material. The top 2 of this plug is formed as an extrados 5 of an arch and the theoretical intrados is indicated by the dotted line 3. The plug is so designed that the arch 4 disposed between the lines 2 and 3 is normally capable of supporting the superstructure of the dam disposed above it. It is well known that a beam which is short as compared with its thickness, will have an interior arch action and I make use of that principle in this construction. The portion of the plug beneath the line 3 will rest upon the material A and B and when the load is thrust upon the plug from the superstructure of the dam, the tendency is for the arch to deflect, thus setting up tensile stresses at the under side of the arch and 10 in the plug beneath the arch. In Fig. 2, I have shown lines 5 which indicate construction joints and which may be disposed substantially radially of the arch so as to divide the arch into what are in effect a plurality of 15 voussoirs. As the arch deflects, these joints may open up to a certain height, but the structure is so designed that they will not open within the limits of the theoretical arch. At the same time, the material A and B will 20 normally be sufficiently good foundation material to support the masonry in the plug beneath the line 3 and may be good enough to provide some support for the masonry in the arch itself and thus aid the arch in supporting 25 the superstructure of the dam. The construction, however, is designed without taking this into account, leaving it as an additional factor of safety. Of course, where the material A and/or B is relatively good, its 30 supporting power may or may not be considered in designing the arch, this depending upon the conditions of the individual job, but, for the purpose of this illustration, I shall consider that the bearing power of the material A and B is ignored, except in so far as 35 it is considered sufficient to support the concrete below the line 3.

In order to aid in preventing slides such as might occur along the cleavage plane F, I provide a plurality of bracing walls 6 extending transversely of the arch or lengthwise of the dam, these walls extending between the buttresses 7 of the superstructure, these buttresses in turn supporting the water 40 bearing member 8. It is preferable to form the extrados of the arch in steps, as indicated in Fig. 2, and to provide sliding joints 9 between the bracing walls and the arch. Otherwise, an additional stress would be induced 45 in the bracing walls by the load and possible deflection of the arch. It is preferable to have the top 10 of each wall in the same horizontal plane and to make each wall substantially continuous to the bearing material on 50 each bank of the stream. The banks may be

further braced against lateral movement by pouring monolithic concrete between the extrados and the bank, as indicated at 11.

Referring now to Figs. 4, 5, 6 and 7, I have shown an arrangement somewhat similar to what has been just described, except that here the arch 12 is separate from the sub-intradosal concrete 13, this concrete being placed between the intrados 14 of the arch and the bed of the stream exemplified by the top of the material A and B. The arch is carried completely across the material A and B to solid rock at C and on its extrados 15 it supports the superstructure of the dam, here indicated as buttresses 7 supporting the deck 8. The bracing walls 6 and monolithic concrete 11 may be used here as in the other embodiment, to take up side thrust, as from material above the fault F.

The load on the dam constructed according to this embodiment will cause a deflection of the arch 12, but as this arch is in direct contact with the sub-intradosal concrete beneath it, the tendency to deflect is resisted by this concrete, and the material A and B thus is permitted to carry all of the load that it can. The remainder of the load will be transmitted in direct thrust to the solid material at the abutments of the arch. If the load on the dam is removed, the sub-intradosal concrete may or may not rise as the load returns to its initial position. When the dam is again loaded, however, the arch will deflect and again come in contact with the upper surface of this sub-intradosal concrete.

In designing the arch of this embodiment, care should be taken to prevent adhering of the sub-intradosal concrete 13 to the intrados of the arch, because this would prevent the functioning of the structure as designed. The bond between the arch and the sub-intradosal concrete may be prevented by coating the surface of one or both with some material such as oil or a thin asphalt paint.

In the form shown in Figs. 4, 5, 6 and 7, there must be considered the effect of back water loading that may occur when a structure of this type is placed in a river bed section. According to this invention, back water is permitted to pass from the extrados to the space between the intrados and the top of the sub-intradosal concrete, which may be formed by deflection and subsequent rising of the arch, or by settlement of the sub-intradosal concrete. The water may be admitted by means of drain pipes 16 through the arch or by inlets 17 which are here shown in the form of grooves in the upper surface of the sub-intradosal concrete, which grooves run transversely of the arch. The ends of the pipes 16 are disposed in these grooves which may conveniently be filled with porous material 18. These fillers may be formed of porous mortar which will permit water to pass lengthwise of the grooves and thus a pres-

sure is permitted to build up on the intrados of the arch, which pressure will be equal to the pressure from the water on the extrados. This arrangement provides equal pressure 5 on both sides of the arch and therefore will lighten the weight of the arch barrel to a certain extent.

I claim:—

1. A masonry dam extending across an area of poor bearing material beneath it and having a foundation formed of an arch extending across said area with its abutments on solid material on opposite sides of said area, a superstructure supported at least in 10 part on said arch, and masonry closing the space beneath the intrados of said arch, whereby deflection of the arch will transfer part of the load on the arch to said masonry and thence to said poor bearing material.
2. A masonry dam extending across a depression in the ground and comprising a superstructure, a foundation supporting said superstructure and comprising an arch extending across the lowest part of said depression, means closing the space beneath the intrados of said arch, and walls extending from 15 said arch to the material on the sides of the depression to transmit thrust to the arch from said material.
3. A masonry dam extending across a depression in the ground and comprising a superstructure, a foundation supporting said superstructure and comprising an arch extending across the lowest part of said depression, means closing the space beneath the 20 intrados of said arch, and masonry disposed between said arch and the material on the sides of the depression to transmit thrust from said material to the arch.
4. A masonry dam extending across an area of poor bearing material beneath it and having a foundation formed of an arch extending across said area with its abutments on solid material on opposite sides of said 25 area, masonry closing the space beneath the intrados of said arch whereby deflection of the arch will transfer part of the load on the arch to said masonry and thence to said poor bearing material, and means preventing 30 the sub-intradosal masonry from forming a joint with the masonry in said arch, whereby the arch may act independently of said sub-intradosal masonry.
5. A masonry dam extending across an area 35 of poor bearing material beneath it and having a foundation formed of an arch extending across said area with its abutments on solid material on opposite sides of said area, masonry closing the space beneath the intrados of said arch, and means for admitting 40 back water to the space between the intrados of the arch and the top of the sub-intradosal masonry.
